LADDER

George E. Reagle, Jamestown, N.Y.

Application March 2, 1951, Serial No. 213,646

2 Claims. (Cl. 228—59)

1

This invention relates to improvements in ladders and particularly to extension type ladders and to rail structure that includes special means for supporting the rungs.

Additionally, the invention relates to improvements over my Patent #1,961,781, granted June 5, 1934. This patent related particularly to structure by which to provide additional support for the rungs of previously constructed ladders, and also to provide support for rungs that had become weakened through wear or strain in use.

Ladders of the rung type, as distinguished from those having steps, become unsafe after being in use for a period of time due principally to the fact that the rung ends become split or, as from exposure to the weather, rot out at their jointure with the rails. It is well known that ladders are required by law to be sold in an unpainted condition. For the most part, carelessness on the part of the purchaser of such ladders is responsible for their not being painted or otherwise protected against deterioration from more or less continual exposure to the detrimental effects of all kinds of weather. Of course, the weakest part of a ladder, and also the most dangerous to a user, is the place of interfitting of rungs with side rails. In all instances, the rung ends project into openings in the side rails. These ends are not exposed to view and, therefore, it is difficult to determine, until an actual break occurs, whether or not the rung end is sufficiently sound and of such condition as to support the weight of a user.

It is a purpose and object of the present invention to provide a construction for rung type ladders that will adequately serve its purpose almost without regard for loads imposed on the rungs.

It is a purpose and object of this invention to provide a rung type ladder having reinforcing means to increase the strength and durability of the rails and rung ends.

It is also an important object of the invention to provide a ladder that, although including the usual wood rails and rungs, is reinforced against bowing through the use of appropriately located metal reinforcing strips.

Another and important object of the invention lies in the provision of ladder rung supports that eliminate the previous requirement of nailing the rungs directly to the ladder rails. In this connection, it is pointed out that the weakest point in all conventional ladder rails is at the aperture for the rung and the place of nailing.

Other objects and advantages of the invention will be more fully understood from a considera-

2

tion of the following specification, taken in conjunction with the accompanying drawing; and in which

Fig. 1 is a perspective view of a portion of a ladder in which one form of the invention is embodied;

Fig. 2 is an enlarged vertical sectional view, taken substantially on the line 2—2 of Fig. 1;

Fig. 3 is an enlarged vertical sectional view, taken substantially on the line 3—3 of Fig. 2; and

Fig. 4 is a fragmentary perspective view of one rail strap and one of the rung supports formed from said strap.

Referring more particularly to the drawing, the reference numeral 10 is employed to generally designate a ladder embodying one form of the present invention. This ladder may be of any suitable length and comprises a pair of rails 11 and a plurality of rungs 12. The inner face 13 of each rail is formed with a wide, shallow recess 14. Furthermore, each rail is drilled to provide the required number of rung receiving openings 16, the spacing of such openings being preferably uniform throughout the length of the ladder, but subject to different dimensional span, depending on the particular type of ladder. As is customary, the openings 16 do not extend completely through the rail, not only for the purpose of improving the rail appearance but also to give added strength thereto by the continuing portion 17.

It is proposed to provide a metal strip 18 for each rail. Each strip 18 is formed of fairly heavy gage material and is of a width to fit snugly in the grooves 14 of the rail. These strips preferably extend the full rail length, although it is contemplated that they may terminate short of the rail ends, provided they stop above and below the top and bottommost rungs of the ladder. A plurality of rung supports 19, in the form of saddles, extend inwardly from one face of the strip. Although these supports may be in the form of separate brackets, welded or otherwise joined to the strip 18, it is found preferable and less costly to form the supports directly from the strip itself. In Fig. 4 of the drawing it is clearly shown that the body 21 of each support, prior to its being shaped into saddle form, is of the proportions of the opening 22 in the strip. In order that the support 19 may have adequate rigidity in its horizontally bent position, the central, inner part of the curved portion and adjacent part of the strip are formed with connected ribs 23 and 24. Although these ribs are not of considerable proportions, they obviously, as can be

seen in Fig. 3 of the drawing, serve to adequately

rigidify or brace the rung support. The rear marginal edges 26 of each of the supports is formed with an upwardly offset prong 27. These prongs are also formed from the stock of the strip, as is clearly indicated by the pointed slots 28 which are continuations of the opening 22 from which the support 19 is formed. The offset of the prongs 27 is for the purpose of permitting their entering and resting against the opening 16 of the rail 11.

In the present illustration of a ladder, it will be noted that rungs 29 include ends 31 of lesser diameter. These ends are intended to press fit the openings 16 and do so by reason of the crowding effected by the prongs 27.

To assemble a ladder embodying the present invention it is of course necessary to provide the shallow recesses 14 in the rails. Strips 18, previously cut to desired length and stamped to provide rung supports, as already brought out, are next placed in the grooves 14. Each strip is flush with the inner face of the rail to which it is applied and is anchored to said rails with screws or nails 32. It has been found convenient to locate four such screws directly beneath each rung support and two directly above, but it will of course be understood that the number and position of these screws may be changed as required. After the strips 18 have been mounted and secured to the rails, corresponding ends 31 of rungs 29 are projected through the openings 22 of the strip and forced into the rail openings 16. As already mentioned, the rail ends have a snug fit due to crowding of the prongs 27, this crowding being such that the prongs are actually more or less pressed into the under surface of the rung ends. At the place of meeting of the ends 31 with the larger diameter portion of the rung, there is of course a shoulder 33. The lower part of this shoulder rests against the offset flanges 34 of the prongs 27. After the proper number of rungs 29 have been engaged with one of the rails, two screws or nails 36 are projected through openings 37 in the supports 19 into engagement with the rungs. Following securing all of the rungs to the supports carried by one rail, the other ends 31 of the rungs are projected into the openings in the other rail and secured in the manner above described.

It will be observed that the present invention not only provides a metal reinforcement for each wooden rail, but also in part relieves the rails from full support of the rung ends through the extending metal supports 19. Furthermore, it will be noted that no toe-nailing is required to anchor the rung ends to the rails. The entire anchoring of the rungs is accomplished through the use of screws or nails 32 and 36 that at distant points engage rail and rung. The invention also finds advantage through the combination of wood with metal reinforcements in enabling the use of lighter weight and thickness rails. It is well known that the greatest strain on the rail of a ladder comes through edgewise bowing and it is evident that the metal strips

provided in the present invention so materially prevent such bowing as to enable the use of lighter weight or smaller stock for rails. Through the use of lighter weight rails it is not only possible to absorb the cost of the additional metal strips, thus rendering a ladder constructed in accordance with the invention no more expensive than a conventional ladder, but it is also pointed out that ladders of this type are, at best, 10 unwieldy and difficult to maneuver, and through the use of lighter weight rails, and possibly light weight metal strips, the ladder of the invention may be easily maneuvered from one position of use to another.

15 Although applicant has shown and described only one modification of the invention, it will be apparent that variations in the structure thereof may be made without departing from the spirit and scope of the invention as set out in the annexed claims.

20 Having thus set forth my invention, what I claim as new and for which I desire protection by Letters Patent is:

25 1. A rung type ladder comprising a pair of wooden side rails, metal reinforcing strips for said rails, each of said strips being mounted in a recess on the inner side of each rail and secured in a position flush therewith, a plurality of saddle-like rung supports formed integral with and extending at right angles to the direction of the length of each strip, each of said supports 30 registering with a rung-end opening in said rail, a rung end mounted on each support and extending into the corresponding side rail opening, and means forming part of said strip projecting into said rail opening and serving to 35 wedge-secure the rung end.

2. A rung type ladder comprising a pair of wooden side rails, metal reinforcing strips for said 40 rails, each of said strips being mounted in a recess on the inner side of each rail and secured in a position flush therewith, a plurality of saddle-like rung supports formed integral with and extending at right angles to the direction of the length of each strip, each of said supports being 45 substantially coincident with the bottom of the openings in said rails, a rung end mounted on each support and extending into the corresponding side rail opening, integral means serving to rigidify said supports with said strips, and prongs integral with said supports projecting into the bottom of said openings and serving to wedge-secure the rung ends.

55 GEORGE E. REAGLE.
